UNITED STATES PATENT OFFICE.

HIRAM D. LAYMAN, OF PORTAGE, PENNSYLVANIA, ASSIGNOR OF ONE-HALF TO
FLORENCE P. LAYMAN, OF PORTAGE, PENNSYLVANIA.

RADIATOR.

1,251,898.

Specification of Letters Patent. Patented Jan. 1, 1918.

Application filed September 16, 1916. Serial No. 120,513.

To all whom it may concern:

Be it known that I, HIRAM DOUGLAS LAYMAN, a citizen of the United States, residing at Portage, in the county of Cambria and 5 State of Pennsylvania, have invented certain new and useful Improvements in Radiators, of which the following is a specification, reference being had to the accompanying drawings.

10 This invention relates to certain improvements in radiators and it is an object of the invention to provide a novel and improved device of this general character which is capable of swinging adjustment relative to 15 the source of heat supply.

It is also an object of the invention to provide a device of this general character having novel and improved means whereby the water of condensation within the radiator 20 may be readily and conveniently discharged therefrom.

The invention consists in the details of construction and in the combination and arrangement of the several parts of my improved radiator whereby certain important 25 advantages are attained and the device is rendered simpler, less expensive and otherwise more convenient and advantageous for use, all as will be hereinafter more fully set forth.

30 The novel features of the invention will hereinafter be definitely claimed.

In order that my invention may be the better understood, I will now proceed to describe the same with reference to the accompanying drawings, wherein—

Figure 1 is a view in elevation illustrating a radiator constructed in accordance with an embodiment of my invention; 40 Fig. 2 is a sectional view taken substantially on the line 2—2 of Fig. 1, a second position of the radiator being indicated by dotted lines; and

Fig. 3 is an enlarged fragmentary vertical 45 section illustrating the rotatable head with which the radiator is connected, the adjacent portion of the radiator being shown in fragment.

As disclosed in the accompanying drawings, P—P denote metallic plates of predetermined configuration and secured one to the other at predetermined points, as indicated at 1.

50 Pressed from each of the plates P are the 55 grooves 2 adapted to register to afford as-

cending and descending conduits in communication one with the other and with the grooves 3 adjacent the lower marginal portions of the plates whereby the same, when in register, afford a return for the water of 60 condensation, said return afforded by the grooves 3 being in continuation of the conduits afforded by the grooves 2.

The lower bends interposed between the ascending and descending conduits have in 65 communication therewith the channels 4 which are also in communication with the return so that the water of condensation collected therein may be readily passed to said return. The conduits 4 are also formed 70 of registering grooves pressed from the plates P.

H denotes a head which is operatively engaged with the adjacent ascending column through the medium of the nipple 5 as is 75 believed to be clearly shown in Fig. 3, while the discharge end of the return is in communication with the head through the medium of the nipple 6.

The nipple 6 is also in communication 80 with the carry-off pipe 7 leading to a suitable point of discharge and through which the water of condensation is adapted to be passed. The head H is provided with a depending extension 8 which is in communication with the steam lead pipe or column S and which also affords a means whereby the head H may be rotated so that the radiator 85 may be readily swung into differing positions relative to the wall of the room or to the pipe S.

The extension 8 is also disposed through the stand 9 with which is operatively engaged the stationary table 10 provided with the upstanding flanges 11 interlocking with 95 the head H so that said head H will be maintained in applied position in a firm manner yet at the same time be readily capable of the requisite axial rotation.

Interposed in the pipe 7 is the gravity 100 valve 12 preferably of a leaf type and which is normally in a closed position, but it will be perceived that upon accumulation of water of condensation within the return of the radiator the head of said water will 105 cause the valve to assume an open position so that said water of condensation may be readily carried off through the pipe 7.

It is to be understood that under normal steam pressure the valve 12 is closed so that 110

there will be no circulation of steam through the pipe 7.

From the foregoing description, it is thought to be obvious that a radiator constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

20 I claim:

1. In combination with a steam radiator and a stationary steam supply pipe, a head mounted for turning movement relative to

the steam supply pipe and operatively engaged with the radiator, said head affording 25 communication between the radiator and the supply pipe, and a return leading from the radiator and extending through the head and within the supply pipe.

2. In combination with a steam radiator 30 and a stationary steam supply pipe, a head mounted for turning movement relative to the steam supply pipe and operatively engaged with the radiator, said head affording communication between the radiator and 35 the supply pipe, a return leading from the radiator and extending within the head, and a check valve interposed in the portion of the return within the head.

In testimony whereof I hereunto affix my 40 signature in the presence of two witnesses.

HIRAM D. LAYMAN.
